ABSTRACT

In a gas separation system utilizing reversing heat exchangers which employ a reheat stream to facilitate heat exchanger temperature control and cleaning, the improvement including at least a pair of particulate filters placed at the heat exchanger feed stream outlets arranged to automatically be cleaned by a portion of the reheat stream without producing objectionable pressure differentials within the gas separation system.

GAS SEPARATION SYSTEM

BACKGROUND OF THE INVENTION

This invention relates to improvements in gas separation systems particularly of the type very aptly disclosed in U.S. Pat. No. 2,460,859, from which much of the instant disclosure has been taken for purposes of setting forth the environment of this instant invention.

This invention relates to an improved method and apparatus for the separation of gas mixtures containing lower and higher boiling components and other components which boil at still higher temperatures. More specifically, it is concerned with a continuous method for the separation of air into a substantially oxygen-containing fraction, and a substantially nitrogen-containing fraction and elimination from the air of undesirable impurities, such as water vapor and carbon dioxide or other high boiling components.

The separation of low-boiling gas mixtures, for example air, into relatively pure components heretofore has been accomplished by processes involving expansion, liquefaction, and fractionation. In processes of this character, heat exchangers have been employed to pre-cool the gas mixtures by counter-current heat interchange with backward-returning cold product material. When the process is conducted under high pressure, the undesirable higher boiling impurities, such as water vapor and carbon dioxide or hydrocarbons, are eliminated by the employment of switching heat exchangers or by absorbers and adsorbers. However, when the separations are conducted under relatively low pressures, only the aforementioned switching heat exchangers generally are utilized to remove the higher boiling components. One major difficulty prevalent in such use of switching heat exchangers arises from the fact that the water, carbon dioxide, or other comparatively higher boiling components in the air will precipitate therefrom as a solid and accumulate in the exchangers in deposits great enough to plug up the passageways of these vessels. The plugged exchanger then has to be switched with an unplugged one and thawed out before again being used. Consequently, the economy of a system using switching exchangers in this manner is greatly reduced because of the necessity to cover the cold losses.

The separation of air, or other normally gaseous mixtures, into the relatively pure components also has been accomplished by a method which includes compressing and precooling of the mixture, liquefaction at the initial pressure of a portion of the mixture by heat interchange with cold products of the separation, the expansion of another portion with external work, fractionation of the two portions in a common fractionating tower at the lower pressure, and backward return of the products of separation.

A counter-current reversing cold exchanger system have been developed which permits a simultaneous and efficient heat interchange between passageways containing counter-currently flowing streams of air and backward returning cold products. This exchanger comprises a plurality of parallel paths for the fluid in each passageway which are so metal bonded together as to establish a metal to metal thermal contact throughout the whole contact length of the vessel. Likewise the several passageways of the exchanger are joined with metal to metal contact.

These reversing heat exchangers are also normally utilized to remove almost all of the higher boiling impu-

rities from air, or other gaseous mixtures, particularly for separations conducted at relatively low pressures, such removal being accomplished by periodically alternating the flow of warm incoming feed and a backward-returning cold product between at least two passageways of the exchanger. That is, during one half of the reversing cycle when the air is being cooled, water and carbon dioxide, for example, are precipitated therefrom and accumulated in solid or liquid phase on the metal surfaces of the passageway through which the air at that time is flowing. Then, before the accumulation has become great enough to plug that passageway the counter-current heat exchange with each other to an extent sufficient to establish conditions suitable to bring about re-evaporation of the deposited solid impurities by less mass quantity of expanded output product than the air from which they are precipitated.

Despite the effectiveness of this system in removing carbon dioxide and other impurities by deposition upon the metal heat exchanger surfaces, it has been found that minute quantities of such impurities are carried from the heat exchangers by the feed stream down through the process steps. Because these steps involve lower temperatures, these impurities remain in the solid state and may accumulate to foul the operation of valves, nozzles, instrument lines, etc. While cyclone separators have been used at the outlets of the heat exchangers to entrap such impurities, they are ineffective in removing particulate impurities in the order of 2 to 10 microns. The use of porous filters at this point in the system would ordinarily be considered impractical because of the substantially large pressure drops they would impart to the waste stream.

SUMMARY OF THE INVENTION

The instant invention pertains to the method and apparatus for using a particulate filter in a gas separation system such as of the type above described wherein such filter is arranged to remove particulate impurities from the feed stream leaving the heat exchangers without imparting an objectionable pressure differential within the system upon reversing of the heat exchanger streams.

It is another object of this invention to employ a particulate filter in said gas separation system for the purpose of entrapping particulate impurities in the order of 2 to 10 microns.

More particularly it is an object of this invention to employ a particulate filter in said gas separation system for the purpose of entrapping carbon dioxide particles in the order of 2 to 10 microns.

It is a further object of this invention to provide a particulate filter means to said gas separation system for removing impure solidified particles which may be cleaned without imparting undesirable pressure differentials within the gas separation system.

It is still another object of this invention to provide a particulate filter means to said gas separation system which is automatically cleaned upon reversing of the feed and waste streams.

Other objects and advantages may become apparent as this description proceeds to describe the invention.

In the accompanying drawings, FIG. 1 is a diagrammatic flow sheet depicting one exemplary embodiment of my invention in connection with an illustrative processing arrangement for producing pure oxygen from air by a continuous low pressure method, involving re-

versing heat exchangers, which is capable of operations of long duration. While the items of equipment shown in the drawing for illustrative purposes are particularly designed for use in a small mobile plant adaptable to installation on the chassis of a motor truck, it is to be understood that the present invention is equally adaptable to large commercial plant installations. Furthermore, the present invention is not limited in its scope to processes involving the separation of air, since it is equally applicable to separations of other gaseous mixtures which contain higher boiling impurities such as, for example, rare gases and normally gaseous hydrocarbons. In the embodiment shown in FIG. 1, backwardly returning low pressure nitrogen-containing product utilized in the auxiliary heat interchanger is used to carry out the cleaning of the filter.

FIG. 2 shows a portion of the flowsheet of FIG. 1 and illustrates an alternative form of the invention in which a portion of the compressed incoming air is used to carry out the cleaning of the filter.

Referring now to the drawing, atmospheric air which in this instance is at 120° F. and atmospheric pressure which preferably has been prefiltered is drawn into the first stage compression chambers 1, 2, 3, and 4 of compressor 5 through intake ports 6, 7, 8, and 9. Compressor 5 is shown on the drawing as being a comparatively small and compact air cooled compressor which is driven by an air cooled internal combustion engine 10, especially adaptable for use in a mobile type plant. The partially compressed air is discharged from the first stage compression chambers through outlet lines 11, 12, 13, and 14 respectively into line 15 and conveyed therethrough to intercooler 16. In intercooler 16, the temperature of the air is reduced to about 135° F. Usually, as there is not condensation of water from this temperature reduction in intercooler 16, the cooled air is passed directly to compression chambers 17 and 18 by way of lines 19 and 20 respectively for a second stage compression to the desired final operating pressure which, in the present instance, is about 105 lbs. per square inch absolute. At this pressure the air leaves compression chambers 17 and 18 through lines 21 and 22 respectively, at about 410° F., whereafter they are combined in line 23 for passage to aftercooler 24. Aftercooler 24 and intercooler 16 comprise finned-tube heat exchangers cooled by a blast of fan-driven air. In passing through the aftercooler the temperature of the air again is reduced to about 135° F. This reduction in temperature at the final pressure condenses most of the water vapor which is withdrawn by a means not shown on the drawing. The partially dried air is then passed to filter chamber 25 by way of line 26 for removal of oil carried over from the compressor, or other impurities such as light hydrocarbons. Upon leaving filter 25 through line 27 the air may have the residual amounts of water removed by passage through an absorber means, again not shown on the drawing. In any event, the air is discharged from line 27 into the inlet port of reversing valve 28. Exchanger 29 is shown in line 27 for heating the filtered air with hot effluent from the second stage of compressor 5 which is taken from and returned to line 23 by lines 30 and 31 respectively. Since heat exchanger 29 is an auxiliary apparatus for delivering an emergency supply of hot air through line 27, it normally is not in use.

During the operation in one phase of the reversing cycle, the now substantially dried and filtered air is

taken through the four-way reversing diverter valve 28 and passed through the inner annuli 32, 33, 34, and 35 of revering heat exchangers 36, 37, 38, and 39 respectively. These reversing exchangers may have their annuli and center passageway packed with a continuous coil of edgewound metal ribbon 87 closely bonded to the metal walls of the exchangers, or the exchangers may be otherwise constructed of the flat plate type, a primary requisite being that the passages are metal to metal bonded to provide a small thermal resistance for the conduction of heat. Optionally there may be only one exchanger having the necessary heat exchange surface. In passing through annuli 32, 33, 34, and 35, the pressured air is in counter-current heat interchange with the cold products of its subsequent separation, as shall hereinafter be described. By such heat interchange the temperature of the pressured air is lowered during its passage through heat exchangers 36, 37, and 38 to approximately -150° F., and it is at this temperature that the air enters the last heat exchanger 39 in the series. In heat exchanger 39 the temperature of the air is further reduced to the order of about -253° F. after which it is withdrawn through line 40, filter 88, unidirectional float check valve 41 and line 42 and introduced into surge drum 43. During its course through the foregoing temperature reduction, the pressured air deposits residual amounts of water on the metal surfaces of the exchangers as liquid and frost and similarly its carbon dioxide constituent is laid down as a solid normally in the last annulus 35 of exchanger 39. Any carbon dioxide snow which may have been carried out of exchanger 39 is trapped in filter 88. Filter 88 may employ any of a number of dry filter media capable of filtering particles in the order of 2 to 10 microns at about -250° F. These would include: Type 304 stainless steel wire mesh as used in a number of pleated mesh filters sold by Fluid Dynamics, Inc., New York, N.Y.; DYNEL, a modacrylic staple fiber of vinyl and acrylic origin manufactured by E. I. Du Pont de Nemours and Co., Inc., Wilmington, Delaware; Media No. FM-004 and FM-003 fiberglass manufactured by Owens Corning Fiberglass Corp., Toledo, OH; and sintered metal filters made by Pacific Sintered Metal Co. of Gardena, Calif.

The purified and cooled air leaving surge drum 43 through line 44 is divided into two fractions. The larger fraction which represents in the present instance approximately 59 percent of the pressured air is taken through line 45 to liquefier 46 for heat interchange with cold backward-returning, nitrogen-containing product. By passing through coil 47 of the liquefier the temperature of this portion of the pressured air is again further reduced to about -274° F. to effect partial condensation and in this condition the air is thereafter introduced by way of line 49 into the inside of reboiler calandria 48 of fractionator 50. Since the temperature of the partially liquefied air is of the order of about -274° F., it is warmer than the bath of liquid oxygen in which calandria 48 is submerged. Consequently, the air gives up heat to reboil the bottoms of fractionator 50 and in so doing reaches a temperature of about -278° F. This temperature causes total condensation of the air to liquid which liquid is thereafter removed from calandria 48 through line 51 for passage through carbon dioxide filter 52 and expansion through valve 53 into the top of fractionator 50. Simultaneously, the smaller portion of the air from line 44, representing ap-

proximately 41 percent thereof, is introduced by way of line 54 into expander 55 wherein its pressure is reduced with work to about 25 pounds per square inch absolute and its temperature correspondingly lowered to the order of -304° F. Under these conditions the expanded air is caused to flow through line 56 having surge drum 57 disposed therein, and injected as vapor feed into fractionator 50 at an intermediate point somewhat below the point of introduction of liquid air from line 51. Bypass line 85, having valve 86, connects line 56 with line 71 for starting up purposes during the period when the air is incompletely cooled.

Vapor to liquid contact is secured in fractionator 50 which brings about separation of the air into a bottoms product which is essentially pure oxygen and an overhead product which contains a preponderance of nitrogen. Pure oxygen vapors are removed from fractionator 50 through drawoff line 58 located immediately above the liquid body of this material in the reboiler section of fractionator 50. Any entrained liquid oxygen is separated from the vapors in separator 59 and returned to the fractionator through line 60. Vaporous oxygen leaves the top of separator 59 through line 61 at a temperature of about -288° F. and is passed through the center passages 62, 63, 64, and 65 respectively of reversing exchangers 39, 38, 37, and 36 for counter-current heat exchange against incoming pressured air which is now passing through annuli 32, 33, 34, and 35 in the present phase of the reversing cycle before it is discharged at a final temperature of 126° F. as product through line 66.

The nitrogen-containing output product is removed as vapor from the top of fractionator 50 through line 67 at a temperature which is of the order of about -290° F. Usually, all of this product is passed from line 67 into line 68 for the counter-current heat interchange in liquefier 46 in which event it is returned to line 67 through line 69. However, it may be desirable at times to bypass a proportion of this nitrogen-containing stream around the liquefier in which case valve 70 is used to control the bypassed proportion. In any event, the total nitrogen-containing stream is caused to flow from line 67 to line 71 at a temperature of about -275° F. for backward return through the aforementioned reversing exchangers 39, 38, 37, and 36 respectively. A temperature of about -275° F. at the inlet to the cold end of the exchanger 39, however, is too cold, relative to an exiting temperature of -253° F. of the pressured air at this end to evaporate all the solid carbon dioxide in the reversed passage 80 of the exchanger through which this output product now flows in the present phase of the reversing cycle. Therefore, in accordance with the present invention, a definite proportion of this cold product is diverted from line 71 through line 72 to heat interchange means 74 for abstracting heat in a desired manner over desired areas of exchanger surface in reversing exchanger 39. The flow through exchanger means 74 is controlled in an amount which is dependent upon the operating conditions in the system by throttling valve 73 in the outlet line 75 for exchanger means 74. Although the heat interchange means 74 is shown as a coil circumferentially around exchanger 39, the invention is not necessarily limited to this form of heat exchange means. For instance, the cold product flowing from line 72 may be passed as readily through any passageway exchanger 39 such as, for example, the center passageway 62 and the oxygen cold interchange

then effected by means of an additional annulus. In any event the diverted proportion of cold product leaves heat interchange means 74 at a somewhat higher temperature level through line 75, whereafter it is returned to the main stream of cold product emitting from line 71 through control valve 76 and the commingled material, in the present phase of the reversing cycle, is then caused to pass through line 77, unidirectional flow check valve 78 and line 79 into outer annulus 80 of exchanger 39.

In the instant invention, a small portion of the cold products leaving heat exchange means 74 is directed from line 75 at a point upstream of valve 73 through line 89, throttling control valve 90, line 91, to unidirectional flow check valve 92 and backwardly through filter 93 to join with line 79. The passage of a portion of the cold products backwardly through filter 93 will cause particulate carbon dioxide and other impurities entrapped therein on the preceeding reversing cycle of operation to subline and be removed from the filter 93. Because the portion of the gas passing backwardly through filter 93 as controlled by valve 90 is very small compared to the total amount of gas being passed backwardly through passage 80 of heat exchanger 39, there is little disruption of the temperature and pressure balance established within the heat exchanger 39. In this manner the temperature of the commingled vapors as they enter annulus 80, in the present instance, is made to be of the order of about -262° F. which establishes a temperature difference at the cold end of exchanger 39 between the incoming pressured air and backward-returning product of about 9° F. The 9° F. difference is less than the maximum allowable temperature difference between the air and product necessary to provide for vapor pressures of the carbon dioxide in these gases that will satisfy the vapor pressure and volume ratio relationship at which complete evaporation of the solid carbon dioxide, or carried-over ice, deposited in annulus 80 during its previous use for the cooling of the pressured air, can be accomplished. The nitrogen gas with evaporated impurities then passes through annuli 81, 82, and 83 to valve 28 where it is discharged at 84.

I have now described the operation of my gas separation system operating under one cycle of operation during which solidified carbon dioxide and other particulate impurities are removed from filter 93 and annulus 80 of heat exchanger 39. During this cycle of operation solidified carbon dioxide and other similar particulate impurities are deposited on the walls of annulus 35 of heat exchanger 39 as well as entrapped within filter 88. After sufficient accumulation of these deposits valve 28 is reversed sending the pressurized air through annuli 83, 82, 81, and 80 of heat exchangers 36, 37, 38, and 39 respectively. This cooled air is then passed through filter 93, check valve 41' into line 42. The nitrogen cold product passing in line 77 passes through check valve 78' through line 40 to annuli 35, 34, 33, and 32 of heat exchangers 39, 38, 37, and 36 respectively. A portion of the cold product discharged from heat exchanger means 74 passes through line 75, line 89, valve 90, line 91, check valve 92', backwardly through filter 88, to become mingled with the cold product passing in line 40 whereby filter 88 is cleaned.

The heat interchange and re-evaporation of precipitated deposits are continuously maintained in reversing cycles in accordance with the foregoing described method.

An alternative embodiment of the invention involves utilization of a portion of the compressed incoming air, after passage through the exchanger, as the cooling medium for use in the auxiliary heat interchanger. This embodiment is illustrated in FIG. 2 in which parts similar in function with similar parts in FIG. 1 are identified by the same reference numeral as in FIG. 1, with the subscript *a*. In FIG. 2 a portion of the compressed incoming air, after passing through exchanger 39a, is diverted from line 42a into line 72a which connects with auxiliary heat interchange means 74a. Line 75a connects the exit of heat interchange means 74a with line 42a down stream of valve 76a located in line 42a. By thus connecting lines 72a and 75a to line 42a and relocating valve 76a the incoming compressed air, after passage through the exchanger, is drawn on for the cooling means. A small portion of the compressed incoming gas after passage through heat interchange means 74a is diverted from line 75a through line 89a, control valve 90a, line 91a, check valve 92a, 20 backwardly through filter 93a to line 79a. The embodiment illustrated in FIG. 2 operates otherwise in the same manner as that of FIG. 1.

It is to be understood that my invention is not to be limited to any of the embodiments described herein for illustrative purposes but only in and by the following claims.

I claim:

1. Apparatus for separating a gaseous mixture at low temperature comprising: a compressor means for compressing a gaseous feed mixture; a heat exchanger means for cooling said feed mixture having first, second, and third passages disposed in heat exchange relationship; separator means for separating the compressed and cooled gaseous feed mixture into components; a first conduit means for conducting a compressed gaseous feed mixture from said compressor means; diverter valve means for alternately connecting said first conduit means to said first and second passages at one end thereof for passing said compressed gaseous feed mixture alternately through said first and second passages; a second conduit means for conducting gaseous feed mixture from said first and second passages to said separator means; a third conduit means for returning from said separator means at least one component of said gaseous feed mixture; a fourth conduit means for connecting the other end of said first passage with said second conduit means; a fifth conduit means for connecting the other end of said second passage with said second conduit means; first and second unidirectional flow valve means disposed respectively in said fourth and fifth conduit means arranged for unidirectional flow in said fourth and fifth conduit means

toward said second conduit means; first and second particulate filters disposed respectively in said fourth and fifth conduit means on the upstream sides of said first and second unidirectional flow valve means; a sixth conduit means for communicating said third conduit means with said other end of said first passage; a seventh conduit means for communicating said third conduit means with said other end of said second passage; third and fourth unidirectional flow valve means disposed respectively in said sixth and seventh conduit means arranged for unidirectional flow in said sixth and seventh conduit means from said third conduit means whereby actuation of said diverter valve means alternates the streams and reverses the direction of flow in said first and second filters; an eighth conduit means; ninth conduit means communicating said eighth conduit means with said fourth conduit means at a point intermediate said first unidirectional flow valve means and said first filter; a tenth conduit means communicating said eighth conduit means with said fifth conduit means intermediate said second unidirectional flow valve means and said second filter; and fifth and sixth unidirectional flow valve means respectively disposed in said ninth and tenth conduit means arranged for flow from said eighth conduit means, said eighth conduit means further communicating with said third conduit means.

2. The apparatus as defined by claim 1 wherein said eighth conduit means is connected to an outlet end of said third passage.

3. The apparatus as defined by claim 2 including a first throttling means in said eighth conduit means for controlling the flow of fluid within said eighth conduit means.

4. The apparatus as defined by claim 3 including an eleventh conduit means communicating an inlet end of said third passage with said third conduit means.

5. The apparatus as defined by claim 4 including a twelfth conduit means communicating the outlet end of said third passage with said third conduit means.

6. The apparatus as defined by claim 4 including a twelfth conduit means communicating that portion of said eighth conduit means upstream of said first throttling means with said third conduit means downstream of its union with said eleventh conduit means; a second throttling means in said twelfth conduit means for controlling the flow of fluid within said eighth conduit means; and a third throttling means in said third conduit means intermediate the connection of said eleventh and twelfth conduit means with said third conduit means.
